(57) **CLAIM**

I claim the ornamental design for a skate board with battery-powered rope light periphery, as shown and described.

DESCRIPTION

FIG. 1 is a bottom perspective view of a skate board with battery-powered rope light periphery showing my new design;

FIG. 2 is a rear elevational view thereof;

FIG. 3 is a front elevational view thereof;

FIG. 4 is a left side elevational view thereof;

FIG. 5 is a right side elevational view thereof;

FIG. 6 is a top plan view thereof; and,

FIG. 7 is a bottom plan view thereof;

1 Claim, 4 Drawing Sheets

FIG. 2.

FIG. 3.

FIG. 4.

FIG. 5.

FIG. 6.

FIG. 7.
